CLAIM

The ornamental design for a display screen or portion thereof with animated graphical user interface, as shown and described.

DESCRIPTION

FIG. 1 is a front view of a first image of a first embodiment of an display screen or portion thereof with animated graphical user interface for a display screen or portion thereof;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a first image of a second embodiment of an display screen or portion thereof with animated graphical user interface for a display screen or portion thereof;

FIG. 8 is a front view of a second image thereof;

FIG. 9 is a front view of a third image thereof;

FIG. 10 is a front view of a fourth image thereof;

FIG. 11 is a front view of a fifth image thereof;

FIG. 12 is a front view of a sixth image thereof.

FIG. 13 is a front view of a first image of a third embodiment of an display screen or portion thereof with animated graphical user interface for a display screen or portion thereof;

FIG. 14 is a front view of a second image thereof;

FIG. 15 is a front view of a third image thereof;

FIG. 16 is a front view of a fourth image thereof;

FIG. 17 is a front view of a fifth image thereof;

FIG. 18 is a front view of a sixth image thereof;

(Continued)

FIG. 19 is a front view of a first image of a fourth embodiment of an display screen or portion thereof with animated graphical user interface for a display screen or portion thereof;

FIG. 20 is a front view of a second image thereof;

FIG. 21 is a front view of a third image thereof;

FIG. 22 is a front view of a fourth image thereof;

FIG. 23 is a front view of a fifth image thereof; and,

FIG. 24 is a front view of a sixth image thereof.

The outermost broken line rectangle shows the display screen or portion thereof, and forms no part of the claimed design.

The portions of the display screen or portion thereof with animated graphical user interface shown in broken lines are included for the purpose of illustrating unclaimed portions of the display screen or portion thereof with animated graphical user interface and form no part of the claimed design.

The appearance of the transitional image sequentially transitions between the images shown in FIGS. 1-6 in the first embodiment, FIGS. 7-12 in the second embodiment, FIGS. 13-18 in the third embodiment, and FIGS. 19-24 in the fourth embodiment. The process or period in which one image transitions to another forms no part of the claimed design.
